UNITED STATES PATENT OFFICE

2,592,030

ELECTRIC WIRE INSULATOR SUPPORT

Donald D. Harding, Avilla, Ind.

Application December 27, 1948, Serial No. 67,478

1 Claim. (Cl. 248—221)

1

This invention relates to improvements in electric wire insulator supports of that type wherein the insulators are mounted upon pins arranged and secured upon cross-arms on a pole.

In ordinary practice poles are erected that have secured to their upper portions wooden cross-arms upon which pins are secured in various ways to support the insulators. Generally, there has been difficulty in maintaining stability between the insulator pins and the cross-arms due to varying climatic conditions. For instance, splitting of the cross-arms frequently occurs because the fastening means used in attaching the pins to the cross-arms become loose or the pins as well as the cross-arms deteriorate, both of which being commonly made of wood.

In the instant invention, the insulator pins are made of cast metal, such as aluminum, and are secured to the cross-arms by screws so arranged as to reduce the likelihood of splitting the grain of the wooden cross-arms.

An object of the invention is to afford insulator pins, light of weight and of great strength, so designed as to provide substantial seating of the pins on the cross-arms, and means for attaching the pins in selected places spaced apart from each other in a manner to avert splitting the grain of the cross-arms to which the pins are attached.

Other objects and advantages of the invention appear in the following description.

An illustrative embodiment of the invention is shown in the accompanying drawings in which:

Fig. 1 is a fragmentary side elevational view of a cross-arm and a pin mounted thereon in which the invention is incorporated;

Fig. 2 is a transverse section of the structure shown in Fig. 1;

Fig. 3 is a fragmentary top plan view of the structure shown in Figs. 1 and 2.

Fig. 4 is a similar side elevational view of a modified form of the invention; and

Fig. 5 is a transverse section of the structure shown in Fig. 4.

The illustrative embodiment of the invention consists of a hollow casting, preferably of aluminum, shaped to form a tapered tubular pin 6, the upper end of which is threaded and has a longitudinal slot 7 extending through its threaded portion. The lower end of the pin 6 has a wide integral base 8 provided with downwardly extending side members 9 and 10 of different lengths, each having in its distal end a nail or screw hole 11. The base 8, together with its side

2

members 9 and 10, constitute a saddle adapted to be positioned astride a cross-arm 12 such as the ordinary wooden cross-arm of a telegraph pole (not shown). The bottom of the base 8 preferably is concave and conforms with the convexity of the top of the cross-arm, so as to become firmly seated and is held thereon when the side members are secured against the opposite sides of the cross-arm by means of nails 10 or screws 13.

The base 8 and the side members constitute a saddle that is disposed astride the cross-arm and fits thereon when in place, the side members being staggered horizontally with respect to the cross-arm, and the nail holes in said side members are staggered vertically respecting each other and out of axial alignment, the purpose being to avoid splitting the cross-arm by the nails or screws 13 that are driven into the cross-arm to secure the side members in place. By this arrangement, the insulating pin structures are firmly secured to the exterior walls of the cross-arms seated thereon, which affords better anchorage for the insulator supporting pins without weakening the cross-arms which is occasioned in the ordinary practice of boring holes through the cross-arms for accommodation of the stems of the usual wooden or metal pins.

In Figs. 4 and 5 are shown pins similar to those shown in the other figures of the drawings. In this instance, the side members 9'—10' extending from the base 8' that has an upstanding pin 6', as in the former instance, and the nail holes 11' in the side members are staggered both vertically and horizontally respecting each other, so that the nails or screws 13' when driven into the cross-arms extend into separate grain laminae of the wooden cross-arms, thus is avoided splitting or shattering of the cross-arms.

In use, the fixtures are shaped so their saddles normally fit the adjacent walls of the cross-arms snugly, and when in place are secured by driving nails or screws through the holes in the distal ends of the side members into the cross-arms at corresponding levels spaced apart from each other.

An advantage of the invention is that the fixtures, once secured upon the cross-arms, may readily be removed therefrom and replaced upon other cross-arms, as in making repairs or renewals. And another advantage is that the fixtures for supporting the insulators (not shown) that are mounted on the threaded ends thereof, in the ordinary manner, may be spaced apart from each other in selected positions on the

cross-arms and secured in place thereon irrespective of any holes that are bored for reception of the ordinary insulator pins.

Variations from the particular construction above disclosed may be resorted to by the exercise of skill in the art, without departure from the spirit or scope of the invention.

What I claim is:

An insulator pin consisting of a hollow casting of non-corrosive and non-magnetic metal, shaped to afford a saddle with a wide base adapted to fit astride a cross-arm, said saddle having downwardly extending staggered side members of different lengths provided with nail holes located respectively in different vertical and horizontal planes in their distal ends, and means driven through said holes into said cross-arm to secure said casting in place.
